UNITED STATES PATENT OFFICE.

JOHN W. PAINE, OF BALTIMORE, MARYLAND.

AUTOMATIC MAIL-ELEVATOR.

SPECIFICATION forming part of Letters Patent No. 276,707, dated May 1, 1883.

Application filed October 4, 1882. (No. model.)

To all whom it may concern:

Be it known that I, JOHN W. PAINE, a citizen of the United States, residing at Baltimore, Maryland, have invented certain new and useful Improvements in Automatic Mail-Elevators, of which the following is a specification, reference being had to the accompanying drawings, forming part hereof, and in which—

Figure 1 is a view in elevation of the shaft or well in which my elevator moves, the openings in each story of a building being shown, the shaft being broken away at each story on account of the great length which would otherwise require to be shown. Fig. 2 is a view, partly in section, of one side of the upper part of the shaft, showing the landing-place for the mail matter in an upper story. Fig. 3 is a section from front to rear, through the shaft, showing a double mail-box and the means for automatically opening and closing its bottom doors. Fig. 4 is a view of the lower part of the mechanism, showing the motor for operating the device. Fig. 5 is a section showing the means for opening and closing the doorway in the shaft in each story. Figs. 6, 7, 8, and 9 are detail views.

My invention is in the nature of an improvement upon the elevator shown in United States Letters Patent No. 258,668, granted to me May 30, 1882; and it consists in the combinations and constructions of parts, which will be first fully described, and then particularly pointed out in claims.

In the drawings like letters indicate the same parts in all the figures.

A is a shaft or well way reaching from the bottom to the top of the building in which the elevator is to be used.

A' is the mail box or car.

B B' are the compartments of the car, of which there are as many as there are stories above the first in the building. b b' are the bottoms of these compartments, which are hinged at c c', and are provided with rear projections, d d', which move in a groove, a, in the rear wall of the shaft or well way, and are composed of spring metal.

d' is a weighted stop, pivoted in the groove a near the top of the shaft, whose purpose is to engage the projections d d' as the car moves upward.

e e' are spring-latches, made each of a single piece of wire, (shown in detail in Figs. 6, 8, and 9,) for holding the doors b b' in position. They are provided with an eye, 4, at the top, through which passes the screw for attaching them to the wall of the shaft. From this eye the wire is carried down double until near the bottom, where each branch is bent outward and forward, (see 5, Fig. 6,) thence inward to each other, Fig. 8, thence together in a diagonal downward and backward direction, as at 6, Fig. 6, thence outward, backward, and inward, the ends being brought together, as seen in Figs. 6 and 9, encompassing the bar g and its attached wedge f or f'.

f f' are wedges for withdrawing the latches e e' to permit the bottoms b b' to drop. Their inclined faces and outer upright edges are of the width of the bar g, and hold the catches back until they are released, in the manner hereinafter described. The sides of these wedges are grooved, as shown in Figs. 6, 7, and 9, the grooves being so deep at the top as to leave only a knife-edge, and gradually decreasing in depth to the bottom, where they disappear.

g is a vertical rod carrying the wedges f f', and having a horizontal slotted projection, g'.

h is a pin moving in the slot in the projecting arm g', which pin projects from one side of a wheel, h', on a shaft, h², and having spurs h³ on its periphery. The shaft h² is mounted in bearings fixed to the top of the car.

i is a pin with which the spurs h³ come in contact as the car is moved upward, thereby turning the spur-wheel a step each time. There is a stop, i, for each story of the building and an extra one near the top of the well-way.

C is the door in the front of the shaft, through which the compartments of the car are emptied, which is so mounted on a hinge, C', that it will normally remain open when not held closed.

C² is a pair of toggle-bars, one being pivoted to one edge of the door C, and the other to one side of the tube in a space provided to accommodate it out of the way of the car, which space is covered by a thin metal plate, so that there will be no exposure of the arms and toggles, and all risk of interference with the move.

ment of the car will be avoided. This space is shown in Fig. 5, the covering-plate being removed.

5 C^3 and C^4 are respectively downward and upward projecting curved arms rigidly attached to the inner end of the toggle-bar C^2 . A pin on the car engages the curved arms in the ascent and descent of the car, as herein-after described.

10 D is a box, one for each story of the building, affixed to the front of the tube to receive the mail matter out of the car.

E is a rope or chain attached to the top of the car.

15 F is a pulley at the top of the shaft, over which the rope E passes down through a box, F' , to the upper one, G , of a pair of compound pulleys, $G G'$, each of which consists of a number independent pulleys mounted side by side 20 on a shaft, Fig. 4, over and under which the rope is alternately passed.

H is a cylinder having heads H' of ordinary form and mounted on bars $K K'$.

I is a piston moving in the cylinder.

25 J are bearings for the shaft of the pulley G , sliding on bars K , the shaft of the pulley G' being in stationary bearings.

L is an endless band or belt passing over pulleys $M N$.

30 L' is a rod or wire attached to the belt L , to the upper end of which is attached a handle, L^2 , inclosed in a box, L^3 , attached to the side of the tube, (see Fig. 1,) which box is closed by an attachment, L^4 , to the door R .

35 m is the shaft of the pulley M .

n is the shaft of the pulley N , which is also the stem of a three-way valve mounted at the junction of pipes $O O'$. The pipes O', O^2 , and O^3 are connected by an ordinary T -coupling.

40 P is a weighted lever, pivoted at P' to the cross-bar P^2 on the top of bar K . p is a pin projecting from the side thereof. At p' on the lever P is pivoted a spring clutch-bar, p^2 . $45 p^3$ is a pin fixed to the wall of the shaft to engage and operate the clutch p^2 .

Q is a stop or projection on the sliding bearing J to engage the pin p on lever P . This stop consists of an upright having a beveled 50 latch at its top, and held in place by a spring, Q' , after the manner of a knife-blade, the purpose of which will be set forth.

R is the door to close the opening in the shaft through which the mail matter is inserted into the car.

55 $S S'$ are the doors to the compartment $B B'$.

T is a bell having a trigger or handle, t .

The lines 1 2 3, Fig. 1, are the different floors of the building.

60 U are screw-holes, in which are the screws for fastening the plate which covers the opening containing the curved arms $C^3 C^4$ and toggle-bars C^2 .

The operation of my device is as follows:

65 The carrier, having unlocked and opened the door R and the doors SS' , (there being as many such doors as compartments and as many com-

partments as there are stories in the building above the first,) inserts the mail in the proper compartment, the upper one containing the 70 mail for the upper story, and so on to the lowest one, closes and locks the doors $S S'$, and

pulls the handle L^2 of the wire L' . This turns on the water, and he may now lock the outer door and proceed on his round, there being no 75 further attention required, the whole device operating automatically. As before stated, the pulling upward of the handle L^2 on rod L' turns on the water. This is done by reason of

the attachment of the rod L' to the endless 80 belt L , the moving of which belt partially rotates the pulley N and with its shaft n , which,

as before stated, is the stem of a three-way valve at the junction of the pipes $O O'$. This allows the water to pass through the pipes O' 85

under the piston in the cylinder H , the pipe O' being attached to any suitable water-supply. The piston I now rises in the cylinder,

carrying with it the bearings J , and per consequence the pulley G . This causes the distance from the pulley G to pulley G' to increase 90

and necessitates the lengthening of the ropes between the pulleys. This can only be done by taking in part of the rope E , which, drawing over the pulley F at the top of the shaft, 95

carries upward the car A' , the distance which it moves upward being the product of the distance the piston moves by the number of times the rope is passed between the pulleys $G G'$.

On its upward movement the car first comes 100 in contact with the curved arm C^4 , (through the pin on the car,) and the arm is pushed by

a pin on the side of the car (not shown) to the right, as shown in dotted lines in Fig. 5, thereby bending the toggle-bars C^2 downward, (also 105 shown in dotted lines in Fig. 5,) thus opening

or allowing the door C to drop to its inclined position across the shaft. (Shown in full lines in Fig. 2 and in dotted lines in Fig. 5.) The movement of the curved arm C^4 to the right 110

throws the curved arm C^3 to the left. (See dotted lines, Fig. 5.) The car being carried a short distance farther upward, one of spurs

h^3 of the wheel h' comes in contact with the first stop-pin i . This turns the wheel one step, 115

causing the rod $g g'$ and its connected wedges $f f'$ to move downward through the medium of the pin h , operating in the slot in the horizontal arm g' . This causes the wedge f' , which

is longer than any of the wedges above it, to 120 move downward into the loop of the spring-catch e , (shown in bottom plan view in Fig. 9,) and draw said catch away from the bottom b' of the compartment B' , allowing said bottom

to drop into the position shown in Fig. 2, thus discharging its contents, which are deflected by the door C into the box or receptacle D .

An alarm is given by the car, as soon as it reaches each story, through the medium of the bell or gong T , its trigger being struck by the 125

car or a projection from it. The car continues on its upward course, opens another door C in the next story above, the spur-wheel is turned

another step by the next pin i , the rod g is driven 130

farther downward, forcing the wedge f' farther into the loop of the catch e' and the wedge f into the loop of the catch e , allowing the next door, b , to drop and discharge the contents of compartments B into its proper receptacle. These operations are repeated at each story until the uppermost compartment is emptied and the car is near the top of the shaft, all the doors b b' , &c., being in the vertical position shown, 10 and all the doors C lying diagonally across the shaft, as shown in Fig. 2. It is necessary that the doors b , b' , and C be all closed and the car returned to the bottom of the shaft, and this operation I will now proceed to describe.

It will be noticed here that the bar g , by reason of the successive lowerings, has advanced the wedges f f' into the loops of the catches e , and these catches are all held back on said 20 wedges, so that if the doors b b' were shut there would be nothing to retain them closed. It is therefore necessary before shutting said doors to put the catches in position to hold them. In order to do this, the car is raised 25 until the spur-wheel is turned another step by contact with the extra pin i , placed, as before stated, above the uppermost opening in the shaft. This moves the bar g down to its lowest position and forces the wedges f f' entirely 30 through the loops in the catches e e' , allowing these catches to spring into position to latch the doors when they are closed up. These latches are now, however, above the wedges f f' , and while they are in position to latch the 35 doors, still the wedges are not in position to release the catches on the next upward movement. Here the function of the peculiar construction of wedges appears, as will be presently explained. On moving the car still farther 40 upward the spring projections d d' in the rear of the doors b b' come in contact with the weighted stop d^2 , causing the doors to close, the whole series being closed successively by this one stop. The car having nearly reached 45 the upward limit of its movement, the stop Q, Fig. 4, comes in contact with the pin p on the lever P and raises said lever. The motion of the pin p in raising being in the arc of a circle described on P' as a center, said pin is 50 moved horizontally with relation to the stop Q, and when a certain point is reached rides off the top of said stop Q, when by its weight it falls. The clutch p' p^2 grasps the belt L, moves it downward with the weighted lever 55 P, and turns the pulley N, thus turning the shaft n , (or valve-stem,) cutting off the water from the cylinder H, and causing it to flow through pipe O' to any suitable wasteway. The lever P falls and carries the belt with it 60 until the clutch-arm strikes the pin p^3 , when its grip on the belt is loosened. The piston, being now relieved of pressure under it, falls gradually by its own weight, the car also falling and taking up the slack of the rope caused 65 by the fall of the piston. The car having now started downward, it is necessary to remove the doors C out of the way. A projection in advance

of the car strikes the bent arm C³, it being in position seen in dotted lines in Fig. 5, and, throwing it into the position shown in full lines in said figure, straightens the toggle-bars, thus closing until opened by the next ascent of the car. As the car passes down, the projections on the rear of the doors b come in contact with the stop d^2 , which simply tips up, allowing them 75 to pass by, and being caused to resume its normal position by reason of its weighted rear end. As the car moves downward the spur-wheel comes in contact with the pins i. This 80 draws the bar g and its wedges upward. This is rendered possible by the spring-latches e e' opening laterally, their ends riding in the grooves in the wedges, as seen in Figs. 7 and 9, until by the successive raisings of the bar g the wedges are carried up entirely above the 85 catches e, ready for a repetition of their work, as first described. The car is now down at the bottom of the shaft, ready to be again sent up. The pipes O² O³ being open, any water which may get into the cylinder above the 90 piston will be forced out at the next upward stroke.

It will be understood that while I have herein described my invention and the best means now known to me for carrying it out, still I do 95 not confine myself to these exact means, as many changes and variations might be made without departing from the spirit of my invention.

Having now fully described my invention, 100 what I claim as new, and desire to secure by Letters Patent, is—

1. In a mail-elevator, the combination of a shaft, a car to receive the mail, adapted to move in said shaft, and means for raising said car 105 and automatically discharging its contents into an upper apartment, as set forth.

2. In a mail-elevator, the combination of a shaft having a door, C, in its wall, a car for carrying up the mail, and means, substantially 110 as described, whereby the door C is made to form a deflector to throw the mail out of the shaft.

3. The combination, in a mail-elevator, of a shaft, a car, means for hoisting the car, and 115 means for automatically dropping the bottom of the car to discharge its contents, as set forth.

4. The combination, in a mail-elevator, of a shaft, a car to receive the mail, and means for automatically opening and closing the door of 120 the car, said means being operated by car, as set forth.

5. The combination, in a mail-elevator, of a shaft, a car to receive the mail, and means for hoisting the car and automatically reversing 125 its motion to lower it, as set forth.

6. The combination, in a mail-elevator, of a shaft, a car, means for raising the car, and means, substantially as described, for automatically closing the door of the car, as set 130 forth.

7. The combination, in a mail-elevator, of a shaft, a car adapted to be raised and lowered therein, a door in the shaft for the insertion

of the mail, a door in the car registering therewith, a door in the bottom of the car, and means, substantially as described, whereby the bottom of the car is dropped and the door C laid diagonally across the shaft to deflect the contents of the car into an upper apartment.

8. The combination, in a mail-elevator, of the shaft, the car adapted to move therein, and having its bottom formed as a door, a door, C, in the shaft, adapted to lie diagonally across the shaft, and means, substantially as described, whereby the lowering of car automatically closes the door of the car and the door C, as set forth.

15. 9. The combination, in a mail-elevator, of a shaft having an opening in each upper apartment, a door to close each of such openings, a car adapted to move up and down in the shaft, and means, substantially as described, whereby such doors are automatically opened and closed by the movement of the car, as set forth.

20. 10. The combination, in a mail-elevator, of a shaft having openings in each upper apartment, doors closing such openings, and means, substantially as described, whereby such doors are held closed until automatically opened by the ascent of a car in the shaft, as set forth.

30. 11. The combination of pulleys M N, mounted on shafts m n, the shaft n being a valve-stem, the weighted lever P, pivoted at P', carrying pin p and spring-clutch p' p², and the moving head carrying spring-stop Q Q', as set forth.

35. 12. The combination of pulleys M N, belt L, weighted lever P, pivoted at P', spring-clutch p², and pin p³ to release the clutch when the weighted lever drops, as set forth.

40. 13. The combination, in a mail-elevator, of the shaft having an opening in its front, a door to fill said opening, toggle-bars pivoted to said door and the wall of the shaft, curved lever-arms rigidly attached to one of the toggle-bars, and a car moving in the shaft, for the purpose set forth.

45. 14. The combination, in a mail-elevator, of a shaft, a car adapted to move therein, the bot-

tom b' of said car, spring-catch e', supporting said door, and bar g, having wedge f' to release said catch, as set forth.

15. The combination, in a mail-elevator, of the shaft, the car having door b', the spring-catch e, the bar g, having wedge f' and slotted arm g', the wheel h', having pin h, and means for rotating said wheel step by step.

16. The combination of the door b', spring-catch e, constructed as described, having a loop, bar g, wedge f', having grooved sides, and means for automatically lowering said bar and wedges, as set forth.

17. In combination, the door b, catch e, wedge f, bar g, slotted arm g', wheel h', having pin h, and spurs h³, all attached to the car, and the pin i, attached to the shaft.

18. The combination, in a mail-elevator, of a shaft having rear grooved wall, the weighted stop pivoted in said groove, the car having door b', and spring-projection d on said door, as set forth.

19. In combination, the shaft having pins i, spur-wheel having pin h, bar g, having slotted arm g' and series of wedges f f', car having compartments closed by door b b', and spring-catches e e', as set forth.

20. In a mail-elevator, the combination, with a shaft, of a car adapted to move in said shaft, and having a series of compartments, a door for each compartment, and means for causing the doors to be opened automatically and successively, as set forth.

21. The spring-catch e, formed of a single piece of wire having eye to receive fastening-screw, vertical arms, ledge for receiving door, and loop through which wedge f passes, the ends of the wire abutting at rear of said loop, in combination with wedge f, having grooved sides, as set forth.

In testimony whereof I have hereto subscribed my name.

JOHN W. PAYNE.
